United States Patent

Des. 236,567
Patented Sept. 2, 1975

236,567

WALL HOOK

Gene Ballin, Locust Valley, N.Y., assignor to Betty Ballin, Locust Valley, N.Y.

Filed Oct. 12, 1973, Ser. No. 406,007

Term of patent 14 years

Int. Cl. D8—08

U.S. Cl. D6—120

FIG. 6

FIG. 2

FIG. 4

FIG. 3

FIG. 5

FIG. 1

FIG. 1 is a perspective view of a wall hook showing my new design;

FIG. 2 is a top plan view;

FIG. 3 is a front elevational view;

FIG. 4 is a side elevational view;

FIG. 5 is a bottom plan view; and

FIG. 6 is a perspective view of a second embodiment of the design shown in FIG. 1.

I claim:

The ornamental design for a wall hook, as shown and described.
